UNITED STATES PATENT OFFICE.

GEORGE E. CHANDLER, OF PROVIDENCE, RHODE ISLAND, ASSIGNOR OF FIVE-EIGHTHS TO ALFRED D. CHANDLER, OF SAME PLACE, AND CHARLES M. LUNT, OF NEWBURY, MASSACHUSETTS.

PUMP.

SPECIFICATION forming part of Letters Patent No. 307,842, dated November 11, 1884.

Application filed September 5, 1883. (No model.)

To all whom it may concern:

Be it known that I, GEORGE E. CHANDLER, of the city and county of Providence, in the State of Rhode Island, have invented a new and useful Improvement in Pumps; and I declare the following to be a specification thereof, reference being had to the accompanying drawings.

Like letters indicate like parts.

10 Figure 1 shows in side elevation my improved pump in position in a well with curb. Fig. 2 is a vertical section of my invention on line $x-x$ of Fig. 3. Fig. 3 is a plan of the inner surface of the lower shell, showing the 15 blades or paddles in position therein. Fig. 4 is a plan of the inner surface of the upper shell. Fig. 5 is a plan of the inner surface of the lower shell without the propelling mechanism. Fig. 6 is a side elevation of my invention. Figs. 7 and 8 show in elevation the blades and the manner of the mounting in the boss of the main shaft, Fig. 7 being partly in vertical section on line $y-y$ of Fig. 8, and Fig. 8 partly in vertical section on line $z-z$ of Fig. 7.

25 My invention relates to the class of submerged pumps; and it consists of a shell or casting, made in two sections, provided with inlet and outlet pipes, and having an interior space of variously-inclined surfaces, within 30 which space one or more sets of paddles or blades are revolved by suitable external mechanism, for the purpose of expelling the water contents of the shell, such blades having a limited reciprocating oscillation as they revolve, 35 which is produced by the combined force of the rotating shaft wherein they are mounted, and of the cam-like action of the several inclined surfaces aforesaid, with which they engage, as hereinafter fully specified.

40 In constructing my improved pump I make a shell, preferably of cast metal, in two sections, A and B, in the form shown in Figs. 2 to 6, inclusive. Said sections have a continuous flange, a , on their outer rim, where they 45 are bolted at intervals, as shown at b . An inlet-pipe, C, and an outlet or discharge pipe, D, open into the central hollow space, which is the interior of the shell. These inner surfaces are formed into a water-way or sluice.

The water enters through the inlet C into a 50 concave passage, c , which, by an incline, d , on the lower section, B, Fig. 5, broadens into a triangular sluiceway, e . (Seen best in Fig. 2.) The sluiceway e continues of about uniform depth until it describes somewhat less 55 than a half-circle, when it rapidly converges by the incline f of the upper shell, Fig. 4, to a shallower concave course, g , leading into the discharge-pipe D.

Arrows marked ' indicate direction of water currents.

E indicates a strainer of wire-gauze to cover the inlet-pipe C.

Thin guide-plates F F', preferably in the form of an arc, bridge the sluiceway and serve to 65 direct and sustain the paddles in their movements.

The upper shell has a central aperture or bore to admit the main shaft, G, and the lower shell has a central seat, h , countersunk in it, 70 to serve as a bearing for the end of said main shaft. At the central parts of the inner surfaces of said sections A and B the metal is cut away in plane steps or bearings $i-j-k$, as shown in Figs. 2, 3, 4, and 5. The plane flat surface 75 h in the lower shell allows the easy passage of the blades, as shown in Figs. 2 and 3, and at the same time prevents the escape of the water without the use of an abutment, as in other rotary pumps.

Having thus described the stationary parts of my device, I will now proceed to specify the moving or operative parts.

Power may be applied by pulley or crank. In Fig. 1 I have shown the pump supported 85 within and upon a well by suitable cross-beams, platforms, and curb, and operated by a crank, H, which, by the beveled gearing I, rotates the main shaft G. The shaft G turns in the direction shown by arrows marked ". 90 At the lower end of the shaft G is a hub or boss, J, having a central bore, which is filled at each side by the bushings K.

Paddle-blades L are rigidly fastened upon arbors M M', and are inclined to each other 95 ninety degrees. The arbor M has its bearings in the hub itself, as shown in Fig. 8, and the arbor M' has its bearings in the bushings K,

as shown in Fig. 7. Said arbor M' is bent at its center into a bow shape, to allow a slight vertical vibration. The necessity of such central bending is to confine the blades consecutively to the same horizontal plane of rotation as the blades of the straight arbor M. The arbors M M' are placed at right angles to each other horizontally.

Illustrating, by reference to Fig. 3, the movement of the blades in their revolution, and giving in said figure a separate designation to each blade for the sake of clearness of description, it will be seen that the blades L' L² are companions on one arbor, and the blades L³ L⁴ are companions on the other arbor. While the blade L' moves horizontally upon the bearing K and guide F, the blade L² is in a vertical position, and while the blade L³ is turned forward to an angle of forty-five degrees by its striking against the incline f of section A, Fig. 4, the blade L⁴ is turned forty-five degrees in the opposite direction by reason of its rigid connection to the same arbor. In the rotation of the shaft G each blade consecutively takes the position shown at L' L⁴ L² L³, in Fig. 3; hence when the water enters the passage e from the inlet-pipe C it is intercepted and cut off by the blade L' as soon as said blade has cleared the guide F and taken its angular position. Continuing its progress, the blade L' comes into a perpendicular position as soon as the companion blade L² has traversed the incline f of section A, Fig. 4, and it maintains its perpendicularity until it is turned by its contact with the incline f, and itself becomes horizontal again. By thus following the blade L' through an entire revolution of the shaft it is evident that said blade first intercepts the current of water at the point marked m on Fig. 3, and then turning toward and into a vertical position propels the water in front of it through the sluiceway e, and at the point marked n on Fig. 3 forces the water into the passage g to the discharge-pipe D. As the blade comes to its horizontal position upon the guide F' of section A, Fig. 4, and within the step-bearing k of section B, Fig. 3, it fills the space k, Fig. 2, and the water can flow in no other course than through the outlet. In this way, by the continuous rotation of the blades and their tilting movement upon their respective arbors, each volume of water within the sluiceway intercepted between the blades is moved bodily forward and lifted into and up the discharge-pipe to any desired height. The height of this water-lift

is limited only by the strength of the blades to sustain the weight of the water-column in the pipe D; hence this pump is admirably adapted for use in mines or deep wells.

60

In its work the pump always has the full capacity of two blades, for of each companion set one blade is in a perpendicular direction, except while passing the inclines d f, and at such times each of the two blades of the set is working at half capacity, thus equaling the full capacity of one blade.

The oscillation of the arbor M', caused by the tilting of its blades upon the inclines d f, is indicated in dotted lines in Figs. 2 and 8, 70 in which such vibration is seen to amount to a quarter-revolution.

By forming the water-course or sluiceway with the several inclined interior surfaces described I secure a gradual turning of the 75 blades in their revolution thereon, instead of having them tilted or tripped suddenly in their course by striking against a stop or spring, as in some varieties of rotary pumps. Such springs, being submerged, soon rust and become inefficient and often break. The blades in my improved pump change their angle of inclination gradually by the shape of the shells alone, and so carry forward and lift the body of water without receiving any shock or concussion. 85 These inclines are cast solid with and are a part of the shells, and hence the blades are tilted and tripped with absolute uniformity and without waste of power.

I claim as a novel and useful invention and 90 desire to secure by Letters Patent—

1. In a rotary pump, the combination of the shells A B, the shaft G, having a hub, J, provided with bushing K, the arbor M, having fixed blades L L and mounted in said hub, 95 and the arbor M', having fixed blades L L and bent bow-shaped at its center, said arbor being mounted in the bushing of the hub, substantially as described.

2. In a rotary pump, the shells A B, united 100 as shown, having an interior sluiceway whose surfaces e d e f g are inclined to each other, as described, in combination with the rotary shaft G, having hub J and bushing K, and the oscillating arbors M M', having blades L L L L, 105 said arbors being mounted, respectively, in said hub and bushing, substantially as described.

GEORGE E. CHANDLER.
